ABSTRACT OF THE DISCLOSURE

A push-button switching device comprising spring-loaded coupling members, arranged along coordinates and provided with permanent magnets and contacts in airtight envelopes actuated by said magnets said device comprising a plurality of push-buttons for the selective actuation of the coupling members.

In push-button switching devices the problem arises of constructing a compact form so that, for example, the device can be incorporated in existing apparatus of given dimensions. It is furthermore important that the basic construction of these devices should allow adaptation to different switching codes used in practice without the need for carrying out drastic modifications from the manufacturing point of view. The desired compact construction involves furthermore the problem of avoiding magnetic stray fields of adjacent permanent magnets which have to actuate an individual contact.

It is known (from Dutch patent application No. 249,668) in respect of push-button switching devices to impart to coupling members arranged along coordinates a movement transverse of the direction of movement of all push-buttons. These coupling members displace permanent magnets connected therewith in the direction of length of stationary contacts arranged in airtight envelopes, so that these contacts are opened or closed.

This known construction has the disadvantage that the orthogonal directions of movement of the push-buttons and the coupling members and the horizontal disposition of the contacts in airtight envelopes require a comparatively large structural volume. Moreover, the nature of this known construction is less suitable for obtaining devices matching different switching codes.

The invention has for its object to provide a construction which obviates said disadvantages.

According to the invention this is achieved by causing the push-buttons and the coupling members to move in the same direction and over substantially equal distances, said direction of movement being parallel to the direction of the parallel longitudinal axes of the contacts in the airtight envelopes.

In an advantageous embodiment of the switching device in accordance with the invention at least one coupling member is T-shaped, the transverse arm of which is located in a plane at right angles to the direction of movement of the push-buttons and extends along one of the coordinates, while there is provided preferably one further coupling member having a recess accommodating a transverse arm of a T-shaped member. A further advantageous embodiment of the invention is characterized in that the device comprises a holder closed at one end by a detachable bottom plate and at the opposite end by a detachable cover plate positioning the coupling members and having apertures accommodating the push-buttons; in the holder the contacts in the airtight envelopes are mounted so that their longitudinal axes are normal to the bottom plate, with the contacts

2

extending through a guide system fixedly arranged between the bottom plate and the cover plate for the coupling members, each of the contacts in the airtight envelope being included in printed wiring on the bottom plate.

5 In a further advantageous embodiment a permanent magnet cooperating with a contact in an airtight envelope is formed by two plate-shaped portions arranged side by side in the direction of movement and polarized in opposite senses transversely of their planes, said portions being preferably arranged in two adjacent, slightly offset recesses, means being provided to urge the two magnet plates in these spaces against stops formed by their relatively staggered positions.

15 The invention will now be described with reference to a drawing which shows an embodiment.

FIG. 1 is a schematic plan view of a switching device embodying the invention suitable for use with a so-called "2-out-of-7 code."

20 FIG. 2 shows a developed view of a switching device embodying the invention suitable for use in telephone apparatus.

FIG. 3 is a schematic plan view like FIG. 1 of a switching device embodying the invention suitable for a so-called "at the most 3-out-of-5" code.

25 The switching device shown in FIG. 1 comprises twelve push-buttons designated by the numerals 1, 2, 3, 4, 5, 6, 7, 8 and 9 and the symbols "-", "0" and "+". These push-buttons are arranged in a matrix (4 rows of 3 buttons or else 3 columns of 4 buttons each) and they are adapted to move at right angles to the plane of the drawing. Each push-button actuates two coupling members of different kind by the cooperation between end faces provided at the push-buttons and the coupling members. One kind of coupling member designated by X₁, X₂, X₃, X₄ is T-shaped, the transverse arms extending parallel to the plane of the drawing in the X-direction coinciding with the direction of the rows and the central limbs being at right angles to the plane of the drawing. These coupling members are adapted to move at right angles to the plane of the drawing. The other kind of coupling members designated by Y₁, Y₂, Y₃, Y₄ has a complicated shape, which will be described more fully with reference to FIG. 2. These Y-members extend in the Y-direction coinciding with the direction of the columns of said array and they are also adapted to move at right angles to the plane of the drawing. When an arbitrary push-button of a given row is depressed, the same T-shaped X-member is invariably actuated. For the push-buttons, 1, 2 and 3 this is the coupling member X₁. In accordance with the column of the selected push-button the coupling member Y₂, Y₃ or Y₄ is actuated. The coupling member Y₁ is always actuated by the depression any push-button whichever in an identical manner by the cooperation with all X-members. The places where the coupling members cooperate with each other and the push-buttons cooperate with the members Y₂, Y₃ and Y₄ are shaded in FIG. 1. The cooperation between the push-buttons and the X-members is not illustrated; this will be apparent from the figure by the overlap of the circumferential lines of push-buttons and coupling members.

60 In order to control seven stationary magnetic contacts in airtight envelopes the coupling members are provided with permanent magnets (shown in FIG. 1 in a dotted plan view), which are displaced upon a movement of the coupling members along said contacts designated by the letters A, B, C, D, E, F, G and A.V.C. The push-buttons "-" and "+," controlling both the A.V.C. contact (general break-contact) for interrupting the microphone circuit in a telephone set, may be employed for local communications and for ingress. All contacts formed in the shape of the known "dry reed" contacts, have their

longitudinal axes normal to the plane of the drawing. For further explanations a survey follows to indicate which push-buttons actuate given coupling members and contacts; it should be noted that the relevant configuration of coupling members, magnets and contacts provides said "2-out-of-7" code, which means that each push-button actuates a combination of two contacts of a total of seven contacts characteristic of said push-button (the AVC-contact being left out of consideration).

Pushbutton	Coupling members	Contacts
1	X ₁ , Y ₁ , Y ₂	A+E+A.V.C.
2	X ₁ , Y ₁ , Y ₃	A+F+A.V.C.
3	X ₁ , Y ₁ , Y ₄	A+G+A.V.C.
4	X ₂ , Y ₁ , Y ₂	B+E+A.V.C.
5	X ₂ , Y ₁ , Y ₃	B+F+A.V.C.
6	X ₂ , Y ₁ , Y ₄	B+G+A.V.C.
7	X ₃ , Y ₁ , Y ₂	C+E+A.V.C.
8	X ₃ , Y ₁ , Y ₃	C+F+A.V.C.
9	X ₃ , Y ₁ , Y ₄	C+G+A.V.C.
0	X ₄ , Y ₁ , Y ₂	D+E+A.V.C.
+	X ₄ , Y ₁ , Y ₃	D+F+A.V.C.
	X ₄ , Y ₁ , Y ₄	D+G+A.V.C.

FIG. 2 shows a switching device embodying the invention, which may be employed advantageously inter alia by its greater speed in telephone sets instead of the conventional selection units comprising the rotatable dial. It will be obvious that especially for this purpose a compact structure is required (the dimensions are prefixed), while magnetic stray fields from the control-magnets have to be at a minimum in order to avoid relative effects. FIG. 2 illustrates all essential elements in their basic form and relationship both for the "2-out-of-7" code and the "at the most 3-out-of-5" code to be described hereinafter. For the sake of clarity the push-buttons "-", "0" and "+," the coupling member X, actuated thereby and the coupling members Y₁ and Y₄, as well as the associated conductors, contacts and the separate coupling members Z to be described with the "at the most 3-out-of-5" code are omitted.

A substantially cylindrical plastic holder 1 is closed at one end by a detachable bottom plate 3 and at the opposite end by a detachable cover plate 5. Between the bottom plate and the cover plate a guide system 7 of a synthetic resin forms an integral part of the holder 1 and is made in common herewith by injection moulding. The holder 1 comprises plastics injection-moulded T-shaped coupling members X₁, X₂ and X₃. The central limbs of said coupling members are guided in apertures of the system 7. The figure shows only the central limbs 9 and 11 of the coupling members X₁ and X₂, which are adapted to slide in guides 13 and 15 of the system 7. Plastics coupling members Y₂ and Y₃ (FIG. 2 shows only two Y-members) extend transversely of the direction of the arms of the T-shaped coupling members X₁, X₂ and X₃ and are provided with recesses 17 and 19 in which parts of the arms of the members X₁, etc., are freely movable. For example, a transverse arm of the T-shaped coupling member X₂ extends across the recess 19 of the coupling member Y₂. The coupling members have a sliding limb (21 on the coupling member Y₂) by which they are guided in the system 7, all corresponding guide paths of which are identical.

Near each of the crossings of one coupling member X and one coupling member Y a plastic push-button is arranged, each of which comprises a press portion and a sliding limb guided in the system 7. The finger-controlled press portion of the button is hollow, the cavity being divided by a partition into two compartments. With the push-button 2 the press portion is designated by 23, the sliding limb by 25 and the two compartments by 27 and 29. The compartments of the buttons 2, 3 and 8 nearest the sliding limbs (compartment 27 in push-button 2) serve for positioning and guiding the T-shaped coupling members X₁, X₂, X₃, X₄, which are provided with guide pieces for this purpose. With X₁ and X₂ the guide pieces are designated by 31 and 33. The coupling members Y

have similar guide pieces; with the coupling member Y₂ shown completely in FIG. 2 this guide piece is designated by 35. The guide pieces of the Y-members, in contrast to those of the X-members, are guided in slits provided on the innerside of the detachable cover plate 5 (for the sake of clarity the slits are not shown in the figure).

The coupling members X are guided on the lower side by their central limbs in the system 7 and on the lower side by means of the press portion of the buttons in the apertures of the cover 5 (see the figure). The coupling members Y are guided on the lower side by sliding limbs in the system 7 and on the upper side directly in the aforesaid guide slits (not shown) in the cover. Between the bottom plate 3 and the bottom side of all central limbs and sliding limbs springs urge the relevant members towards the cover 5; for the sake of clarity these springs are not shown.

An end face (37 of the button 2) located on the lower side of the hollow press portion of the buttons and the upper face of an X-member constitute mutually cooperating end faces of the push-buttons and of the T-shaped coupling members X. A second end face (41 of push-button 2) located on the lower side of the hollow press portion of the buttons and extensions of each Y-member (39 of member Y₃) constitute mutually cooperating end faces between the push-buttons and the recessed coupling members Y.

Each of the coupling members is provided with at least two communicating, relatively offset recesses intended for accommodating each two plate-shaped, permanent magnets polarized in opposite senses transversely of their planes (the magnets 43 and 45 for the member X₁). Said recesses are bounded on one side by resilient ridges, for example, 47 and 49 of the member X₁, which hold the two magnets tight on the stops 51 and 53 formed by the offset positions of the two recesses. With the X-members these recesses are arranged in the central limbs and with the members Y₂ and Y₃ they are located in the sliding limbs (for example, recesses 55 and 57 in the sliding limb 59 of the member Y₂). The contact between the magnets and the stops provides the advantage that the place of the maximum magnetic field-line concentration in the transverse plane going through the line of separation between the magnets is accurately defined not only with an individual coupling member but also in the mutual array of the coupling members. The point up to which the two magnets have to be displaced to actuate the relevant contact can thus be satisfactorily defined. The use of two magnets polarized in opposite senses has the further advantage that said maximum field-line concentration is located in a comparatively small region around said transverse plane. Beyond this region the field-line concentration is considerably lower so that the distance over which the magnets have to be displaced for actuating the contacts may be small (about 6 mms.). Consequently, a transmission mechanism between the push-buttons and the coupling members may be dispensed with. The stroke of the push-buttons must not exceed 6 mms. in order to maintain a convenient control of the switching device. Owing to the omission of a transmission the required structural volume is, of course, smaller so that also viewed in the direction of movement of the push-buttons the device can have a compact form.

Each pair of magnet plates is screened, in order to avoid stray fields, on its side remote from the associated contact by a strip of ferromagnetic material extending over the two magnet parts and arranged in the coupling member concerned.

A contact in an airtight envelope is controlled by an integral or bipartite permanent magnet included in a central limb or a slide limb as stated above. Such a contact is therefore always located near such a limb and extends through an aperture provided for this purpose in the system 7 intended for guiding said limbs. It will be obvious

from the foregoing that each of the said limbs will not be associated with a contact. In order to use only a single mould in the manufacture, the system 7 is provided at the beginning at all places where a contact may be provided in the push-button unit, that is to say in the proximity of the guide member of each limb, with an aperture for the contact.

The contact 61 (and any further contact) is screened on the side opposite the control-magnets concerned by a sheath 65 of electrically conductive material. Near one end of this sheath is provided with an extension 67, which is electrically connected to one of the postions of the contact tongues 69, located outside the envelope of the contact. Near the other end the sheath 65 is provided with extensions 71 and 73, anchored in apertures 75 and 77 in the bottom plate 3. One of these extensions is electrically connected to a printed wiring (not shown) on the other side of the bottom plate 3, to which is also connected a portion 79 of one of the contact tongues located near said end. The sheath 65 is furthermore provided with a tag 81, by which it is held in a slit 83 in the cover plate 5 so that the contact 61 and the associated screening sheath 65 are accurately fixed in place in the device.

As stated above, the press portion of each push-button is hollow, the cavity being divided by a partition into two compartments (see push-button 3 in FIG. 2). One of these compartments serves for guiding the extensions of the X-member (see push-buttons 2 and 5 in FIG. 2), whereas the other compartment serves for guiding a separate coupling member Z (for example 85), the longitudinal axis of which extends parallel to the direction of movement of the sliding member. On the lower side this sliding member is guided like the other coupling members in the system 7. The coupling member Z, the shape of which differs from that of the coupling members X and Y, is required inter alia for obtaining the so-called "at the most 3-out-of-5" code used in practice. The coupling member 85 has an end face 87, which cooperates upon depression of the button 3 with an end face 89 of said button. FIG. 3 shows diagrammatically like FIG. 1 the arrangement for an "at the most 3-out-of-5" code. Near the push-buttons 4, 6 and "+" a coupling member Z (hereinafter designated by Z_4 , Z_6 and Z_+) is provided. The contacts are designated by the letters A, B₁, B₂, C₁, C₂, D₁, D₂, K and AVC, the contacts B₁, B₂, C₁ and C₂, D₁ and D₂ being connected in parallel electrically. The "+" button serves in said "at the most 3-out-of-5" code as the earth-connecting button, which permits consultation. The "-" button may be employed for local communications and ingress. For the sake of clarity a survey is again given of the coupling members and contacts actuated by the various push-buttons.

Pushbutton	Coupling members	Contacts
1	X ₁ , Y ₁ , Y ₂	A+A.V.C.
2	X ₁ , Y ₁ , Y ₂ , Y ₃	A+B ₂ +A.V.C.
3	X ₁ , Y ₁ , Y ₃	B ₂ +A.V.C.
4	X ₂ , Y ₁ , Z ₄	B ₁ +C ₁ +A.V.C.
5	X ₂ , Y ₁	C ₁ +A.V.C.
6	X ₂ , Y ₁ , Z ₆	C ₁ +D ₁ +A.V.C.
7	X ₃ , Y ₁ , Y ₂	C ₁ +D ₂ +A.V.C.
8	X ₃ , Y ₁ , Y ₂ , Y ₃	A+B ₂ +D ₂ +A.V.C.
9	X ₃ , Y ₁ , Y ₃	B ₂ +D ₂ +A.V.C.
0	X ₄ , Y ₁ , Y ₂	A+C ₂ +A.V.C.
+	Z ₊	A+B ₂ +C ₂ +A.V.C.

A comparison between the two surveys shows for the positions of the contacts and the number of contacts actuated by one button that the "2-out-of-7" code is regular. Without drastic changes the basic structures of the push-buttons and the coupling members described with reference to FIG. 2 may serve both for a "2-out-of-7" code and an "at the most 3-out-of-5" code. The most characteristic differences between the two codes are:

(a) A different disposition of the contacts, for which purpose the system 7 is provided already with the appropriate guide paths;

(b) The addition of three coupling members Z, for which purpose all push-buttons are appropriate and the guide paths are provided;

(c) The partially different disposition of the end faces of the Y-members cooperating with the push-buttons.

The items (a) and (b) can be satisfied quite readily, since the system 7 is identical for each code and is only utilized in a different manner. The item (c) can be satisfied by starting from a Y-member having four pairs of extensions, given extensions being removed in accordance with the code to be used.

It will be obvious that the push-button assembly described above can be manufactured at very low costs in mass production, since it consists for the major part of injection-moulded synthetic resin. It is not necessary to adapt the injection-moulding machines to the Y-members for the various codes, since the differences from the basic form are slight and can be eliminated from the basic form by means of existing, simple machines such as sawing machines and grinding machines.

What is claimed is:

1. A switching device comprising:

(a) a frame, (b) a plurality of electrical contacts carried by the frame, (c) a plurality of first coupling members carried by the frame, each movable between actuated and unactuated positions, (d) a plurality of second coupling members, each being movable similarly to the first members and being engagable by at least one first member, (e) a magnet carried by each member, (f) first means resiliently urging said members toward their respective unactuated positions, (g) second means comprising a plurality of elements carried by the frame and movable similarly to said members, each element disposed to engage at least one of said members, whereby movement of each element engages and moves each corresponding member and its magnet, moving same between unactuated to actuated positions with each magnet moved into the vicinity of a contact for actuating same.

2. A device as defined in claim 1 wherein each element engages and moves one first member and one second member, and each moved first member engages and moves one additional second member, whereby the magnets of the three moved members are moved to corresponding contacts.

3. A device as defined in claim 1 wherein said second means comprise pushbuttons.

4. A device as defined in claim 1 wherein each contact is a magnetically operated switch in airtight envelope.

5. A device as defined in claim 1 wherein said frame has a principal axis, said second means comprise push-buttons, said first and second members and the pushbuttons, are movable along lines generally parallel to said axis, each contact is a magnetically-operated switch, and the first and second members respectively have longitudinal arm parts extending along perpendicular X and Y coordinates which are normal to said principal axis.

6. A device as defined in claim 5 wherein there are (a) four first members having four spaced and parallel arm parts generally in a first plane, and (b) four second members having four spaced and parallel arm parts generally in a second and adjacent overlying plane.

7. A device as defined in claim 5 wherein each first member forms a T-shape, with its transverse part forming said arm along the X-axis.

8. A device as defined in claim 5 further comprising a plate including circuitry thereon, the contact being electrically connected thereto.

9. A device as defined in claim 5 wherein each magnet comprises two permanent magnets formed as plates disposed adjacently and polarized in opposite senses.

10. A device as defined in claim 5 further comprising

3,539,958

7

ferromagnetic screening means adjacent parts of each magnet.
